DISPLAY RACK

Michael Wahl, Flushing, N.Y., assignor to Wahl
Associates, Inc., Long Island City, N.Y.

Filed June 17, 1970, Ser. No. 23,528

Term of patent 14 years

Int. Cl. D6—06

U.S. Cl. D80—10

FIG. 1.

FIG. 2.

FIG. 3.

FIG. 4.

FIG. 5.

FIG. 1 is a perspective view of the display rack in accordance with my design;

FIG. 2 is a side elevational view thereof;

FIG. 3 is a front elevational view thereof;

FIG. 4 is a top plan view thereof; and

FIG. 5 is a perspective view of a modified form of the display rack as shown in FIG. 1.

I claim:

The ornamental design for display rack, substantially as shown and described.
